(57) **CLAIM**

The ornamental design for a solar battery affixing frame, as
shown and described.

DESCRIPTION

FIG. 1 is a perspective view of a first embodiment of a solar
battery affixing frame showing our new design;

FIG. 2 is a top plan view thereof;

FIG. 3 is a bottom plan view thereof;

FIG. 4 is a front elevational view thereof, the rear elevational
view being a mirror image thereof;

FIG. 5 is a right side elevational view thereof, the left side
elevational view being a mirror image thereof;

FIG. 6 is a cross-sectional view thereof taken along lines 6-6
of FIG. 2;

FIG. 7 is a cross-sectional view thereof taken along lines 7-7
of FIG. 2;

FIG. 8 is a perspective view of a second embodiment of a solar
battery affixing frame;

FIG. 9 is a top plan view thereof;

FIG. 10 is a bottom plan view thereof;

FIG. 11 is a front elevational view thereof, the rear elevational
view being a mirror image thereof;

FIG. 12 is a right side elevational view thereof, the left side
elevational view being a mirror image thereof;

FIG. 13 is a cross-sectional view thereof taken along lines
13-13 of FIG. 9; and,

FIG. 14 is a cross-sectional view thereof taken along lines
14-14 of FIG. 9.

The broken lines shown represent unclaimed subject matter
and form no part of the claimed design. The dot-dash lines
represent the boundaries between the claimed and unclaimed
portions of the solar battery affixing frame.
